UNITED STATES PATENT OFFICE.

JOHN V. ALLEN, OF SOUTH WEYMOUTH, MASSACHUSETTS, ASSIGNOR TO UNITED SHOE MACHINERY COMPANY, OF PATERSON, NEW JERSEY, A CORPORATION OF NEW JERSEY.

TENSION DEVICE.

1,149,244.

Specification of Letters Patent. Patented Aug. 10, 1915.

Application filed April 7, 1909. Serial No. 488,430.

To all whom it may concern:

Be it known that I, JOHN V. ALLEN, a citizen of the United States, residing at South Weymouth, in the county of Norfolk and State of Massachusetts, have invented certain new and useful Improvements in Tension Devices; and I do hereby declare the following to be a full, clear, and exact description of the invention, such as will enable others skilled in the art to which it appertains to make and use the same.

The present invention relates to tension devices for imparting a yielding resistance to the thread of sewing machines and other machines employing a thread or cord. Heretofore devices for accomplishing this result have comprised as a general rule a rotatable member with which the thread was held in frictional engagement, and some suitable friction device for retarding the rotation of such member. Such constructions, however, have been found defective in operation in that the thread being held simply in frictional engagement with the rotatable member tended to slip thereon, even when the thread was passed completely around the rotating member one or more times or the thread-receiving groove in said member was so shaped that the thread had a wedging or gripping action therein.

One of the objects of the present invention is to provide a tension device which will impart a uniform and unvarying resistance or tension to the thread of the desired and predetermined amount, and this result is accomplished, broadly speaking, by means of a rotatable thread member, the rotation of which is restrained or retarded by some suitable friction device, mechanism being provided for clamping the thread to such member, so that all slipping of the thread on the member is absolutely prevented and the desired amount of resistance or tension is invariably obtained.

Another defect present in the prior devices where the thread-receiving groove of the rotatable member was narrow or V-shaped, so that the thread would have a wedging or gripping action, and the thread made one or more complete turns around such member, was that a chafing or abrading action of the thread upon itself would be produced at the point where the thread was delivered from the bottom of the groove and

from beneath overlying turns to the sewing machine proper. Where wax or other material was applied to the thread before it reached the tension device, not only the wedging action of the thread in the groove but the chafing of the thread upon itself tended to remove or strip the wax from the surface of the thread, which wax was liable to gum or clog up the tension device and to interfere with its proper operation.

Other objects of the present invention are to provide a tension device which cannot chafe or abrade the thread, which shall have a minimum stripping action upon the wax on the thread, and which shall have little tendency to clog or gum up with wax. These objects are accomplished by so constructing the tension device that the thread is gripped or clamped to the rotatable member, thus avoiding the necessity of a narrow or V-shaped thread-receiving groove, or of leading the thread out from beneath one or more superimposed turns or layers thereof, and by so constructing the gripping or clamping means that only a very small portion of the thread is held under pressure. Still another defect inherent in the devices of the prior art, and particularly objectionable in these devices when used upon high speed sewing machines where the thread is intermittently drawn through the tension device at exceedingly short intervals of time, is the necessity of starting the rotatable member from a position of rest, causing it to attain a high angular velocity, and then bringing it to a full stop, all in an exceedingly short space of time.

The present invention seeks to avoid the very objectionable inertia effects due to such a manner of operation by so constructing the tension device that the peripheral speed or angular velocity of the rotatable member shall be less than the linear speed of the thread delivered up by it. Briefly, this is accomplished by providing the rotatable member with a plurality of alternating projections and recesses over and into which the thread is folded or crimped by suitable devices, thus enabling the tension device to give up its thread from such loops or folds at a higher linear rate than where the thread is held by the rotatable member in the ordinary manner.

In the accompanying drawings which

illustrate the preferred embodiment of the present invention devised for use in connection with a chain-stitch, wax-thread, shoe sewing machine of the "Goodyear" type, Figure 1 shows in side elevation a portion of the head and column of such a sewing machine and the tension device attached thereto; Fig. 2 shows in top plan the device as attached; and Fig. 3 shows the tension device detached in side elevation and looking in the opposite direction from Fig. 1.

As shown in the drawings, 1 represents the head of the sewing machine and 2 the column or support for the same. Rigidly secured to the rear portion of the head by the bolts 3 is the tension device which comprises, briefly, a frame, a rotatable thread member mounted thereon, a friction device for retarding the rotation of said member, guiding means for guiding the thread to the rotatable member, and clamping means for clamping the thread to said member.

The frame is indicated by the reference character 4 and is provided at its rear end with the open slot or recess 5 and the vertical and the downwardly extending arms 6 and 7, respectively. The rotatable thread member is shown at 8 and is provided on its periphery with a plurality of projections 9 which resemble gear teeth in shape or outline, the points or crowns of the teeth being somewhat rounded, and the recesses or intervals 10 between the teeth being somewhat wider, than with ordinary gearing, for purposes hereinafter to be stated. The thread member 8 is rotatably mounted upon the shaft or stud 11 located in the slot 5 of the frame and securely clamped to the frame by means of the washer and nut 12 and 13, respectively.

The friction device for retarding the rotation of the thread member 8 comprises two felt washers 14, one on each side of the member and held in engagement therewith on one side by the washer 15 (see Fig. 3) and on the other by the spring pressed washer or block 16. The washer 15 is held from rotation by being clamped between the frame and the shoulder on the shaft, while the block or washer 16, although free to move along the shaft 11, is prevented from turning with the thread member by means of the rounded extremities 17 of the forked end of the tension release lever 18, these ends engaging correspondingly shaped recesses 19 formed in the spring block 16. The tension release mechanism is substantially like that shown in the patent to La Chapelle No. 488,505, dated December 20th, 1892, and therefore need not be described in detail. Surrounding the shaft 11 is the open spring 20, one end of which engages the block 16 while the other end bears against the adjusting wheel or nut 21 on the

threaded end of the shaft, a lock nut 22 being provided for locking the adjusting nut in the desired position.

As shown in Fig. 2, the projections or teeth of the thread member are formed parallel with the axis of rotation and without any groove or slot therein, and in order to guide the thread properly on to these peripheral projections or teeth, a grooved thread truck 23 is pivotally mounted upon the downwardly projecting arm 7 around which truck the thread 24 passes.

The clamping device for gripping or clamping the thread to the thread member is shown in the drawings as a freely rotatable wheel 25, also provided on its periphery with projections or teeth 26 corresponding in outline to the projections 9 on the thread member 8, the recesses 27 between the teeth 26 being formed like the recesses 10 on the thread member 8 of greater width than the teeth.

The wheel 25 is rotatably mounted upon the stud 28 secured in the swinging arm 29 which in turn is pivoted on the stud 30 in the frame 4 of the tension device. The lever 29 is held from movement by means of a latch 31 pivoted on the stud 32 passing through the slot 33 in the arm 6 of the frame, the front end of the latch being provided with a notch or recess 34 to engage the projecting end of the stud 28 upon which the wheel 25 rotates. By means of the slot 33 the pivot of the latch 31 may be moved toward or from the head of the sewing machine, thus adjusting the axis of rotation of the wheel 25 farther from or nearer to the axis of rotation of the thread member 8 and thereby varying the extent the projections 9 and 26 enter the recesses 27 and 10, respectively, or, as it will hereafter be called, the depth of intermesh.

The lead of the thread 24 is from a wax-pot or directly from some suitable source of supply, over the guide truck 23, thence around the front of the thread member 8, between that member and the wheel 25, then partially around the wheel, from which it passes to the head of the sewing machine. The object of making the recesses 10 and 27 of greater width than the projections or teeth 26 and 9 which enter them, is so that the thread may be easily crimped or folded over the projections and down into the recesses, these latter being sufficiently wide to permit this to be done without bringing any considerable pressure upon that portion of the thread between the sides of adjacent projections or teeth and between the tops of the teeth and bottoms of the recesses on the member 8 and wheel 25. The rounding of the teeth is to avoid all possibility of cutting of the thread in the clamping operation.

The mode of operation of this tension de-

vice is as follows: After the thread has been carried through the device in the manner indicated, the latch 31 being drawn back and the lever 29 and wheel 25 being thrown forward into the positions shown in dotted outline in Fig. 3, to facilitate this operation, the pivot for the latch will be adjusted to give the requisite depth of intermesh and the nut 21 will be turned to apply the desired amount of tension. If the sewing machine be now set in operation and the thread be drawn upon by the thread handling instrumentalities, the very first movement of the thread will cause the freely rotatable wheel 25 to turn slightly, causing the advancing faces of its projections or teeth to securely grip or clamp the thread against the following faces of the thread member 8, thus preventing all further movement of the thread except when accompanied by a movement of the thread member 8. The greater the strain exerted upon the thread, the more securely will it be gripped or locked between the projections or teeth on the wheel 25 and those on the thread member 8, so that all slipping of the thread and any variation from the desired and predetermined amount of tension are rendered impossible. Since only a very small portion of the thread 30 is actually subjected to this clamping or gripping action, very little of the wax applied to the thread is squeezed out of or stripped from the same, which results not only in the thread being delivered with a greater quantity of wax, but also greatly reducing the amount left upon the tension device. Furthermore, by reason of the construction of the parts, there is little, if any, liability of the device to gum or clog up with wax 35 or in any other way to have its operation interfered with. It is obvious that as the thread member rotates and delivers up thread, a very considerably greater length of thread will be freed, say by a rotation equivalent to the peripheral distance between two adjacent projections or teeth, than if the thread was held in a circular groove in the ordinary and usual manner. The greater the depth of intermesh and the 40 larger the number of projections or teeth, the greater will this thread excess become and the slower will be the rate of rotation of the thread member relatively to the rate of delivery of the thread, or, to put it in another way, the higher will be the rate of delivery of the thread for a given rate of rotation of the thread member, thus adapting the device particularly to high speed machines, as already pointed out.

Having thus described the construction

and mode of operation of the preferred form of the present invention as applied to a particular type of machine, what is claimed is:

1. A tension device, having, in combination, a pair of intermeshing spur gear wheels between which the thread is laid, adjusting devices for positively limiting the depth of intermesh, and a friction device for retarding the rotation of one of said wheels, substantially as described. 65

2. A thread delivery controlling device, having, in combination, a pair of intermeshing spur gears between which the thread is laid, means for positively limiting the depth 75 of intermesh, and means for controlling the rotation of one of said gears, substantially as described.

3. A thread delivery controlling device, having, in combination, a pair of intermeshing spur gears having relatively narrow teeth and wide spaces between the teeth to permit the gear teeth to grip the thread at separated points along the thread between the following face of the tooth of one 80 gear, and the advancing face of the tooth of the other gear, means for controlling the rotation of said first mentioned gear, and means for positively limiting the depth of intermesh substantially as described. 85

4. A tension device, having, in combination, a rotatable thread member provided with a plurality of projections and recesses, a friction device for retarding the rotation of said member, a second rotatable member 95 having projections and recesses arranged to intermesh with the recesses and projections on the thread member, to carry the thread over the projections and into the recesses on said members, a pivoted lever supporting 100 the second member, and mechanism for adjusting the lever about its pivot to vary the depth of intermesh of the projections and recesses, to alter the linear speed of the thread relative to the peripheral speed of said members, substantially as described. 105

5. A thread delivery controlling device, having in combination, intermeshing gears between which the thread is laid, means for controlling the rotation of one of said gears, 110 and means for supporting the gears to allow a rotary movement of one gear with relation to the other under a strain on the thread to clamp the thread, substantially as described.

In testimony whereof, I affix my signature, in presence of two witnesses.

JOHN V. ALLEN.
